UNITED STATES PATENT OFFICE.

WILLIAM F. ANKLAM, OF DETROIT, MICHIGAN, ASSIGNOR TO C. M. HALL LAMP COMPANY, OF DETROIT, MICHIGAN, A CORPORATION OF MICHIGAN.

LAMP-SOCKET.

1,153,591.

Specification of Letters Patent. Patented Sept. 14, 1915.

Application filed August 31, 1914. Serial No. 859,434.

To all whom it may concern:

Be it known that I, WILLIAM F. ANKLAM, a citizen of the United States of America, residing at Detroit, in the county of Wayne 5 and State of Michigan, have invented certain new and useful Improvements in Lamp-Sockets, of which the following is a specification, reference being had therein to the accompanying drawings.

10 The invention relates to lamp sockets such as employed for the holding of incandescent lamp-bulbs in vehicle lamps, and the invention has particular reference to the construction providing for longitudinal adjustment of the socket in focusing.

In the drawings, —Figure 1 is a plan view of the blank from which the socket is formed; Fig. 2 is a perspective view of the completed bulb-holding socket; Fig. 3 is a 20 perspective view showing the lamp, the holding socket therefor, and the outer socket in which said holding socket is longitudinally adjustable; Fig. 4 is a cross-section through Fig. 3; and Fig. 5 is a longitudinal section therethrough.

A is a sheet metal blank which is provided at one end with a plurality of bayonet joint slots B and also preferably with spring tongues C.

30 D D' are projections from the sides of the blank, the latter being notched or serrated at its edge.

As shown in Fig. 2 the blank A is bent to form a cylinder E, and the projections D D' are bent to extend radially outward, forming longitudinally-extending flanges.

F is an outer socket of a diameter to telescopically receive the socket E and permit the longitudinal sliding thereof.

40 G is a laterally-extending flange on the socket F, which is apertured at H for the passage of the flange D' and is provided at one side of said aperture with an inclined edge I for engagement with the notches in the flange D'.

J is a spring preferably formed of a U-shaped wire secured at K to the flange G and having its free end laterally bent at L to form a bearing upon the flange D.

50 As shown in Figs. 4 and 5, when the sock-

ets E and F are in engagement the tension of the spring J will normally press the notched flange D' into engagement with the inclined edge I of the aperture H and this will lock said sockets from relative, longitudinal movement. When, however, it is desired to longitudinally adjust the lamp socket for focusing, a slight rotation thereof will compress the spring J and withdraw the notched edge of the flange D' from the 60 incline I so as to permit a free longitudinal adjustment of the inner socket. When suitably adjusted the inner socket is released and by the tension of the spring J will again be rotated to lock the notched flange D' 65 with the edge I.

What I claim as my invention is:

1. A lamp socket, comprising a tubular member formed from a sheet metal blank, having a longitudinal serrated edge portion 70 extended radially outward, a second tubular member telescopically engaging the first named member and maintaining the longitudinal edges thereof adjacent, a flange transversely formed upon the outer member 75 having an edge engageable with the serrations of said radially extended edge portion through relative rotation of the two cylindrical members, and a spring mounted upon one of said cylindrical members exerting a 80 rotative force upon the other, tending to maintain the said edge of the transverse flange engaged with said serrations.

2. A lamp socket, comprising telescopically engaged cylindrical members, a longitudinally extending flange on one of said members, a transversely-extending flange upon the other member apertured for the passage of said longitudinal flange, an edge of the aperture being sharpened and a 90 spring secured to the front surface of the transverse flange, bearing upon the longitudinal flange, tending to maintain the latter pressed against said sharpened edge.

3. A lamp socket, comprising telescopically engaged cylindrical members, the inner one being formed from a sheet metal blank, a longitudinally extending flange upon the inner member projecting through an opening in the outer member, and formed 100

by contiguous portions of the member which projected laterally from opposite edges of the original blank, and a knife edged member carried by the outer cylindrical member, normally engaged by the longitudinal flange of the cylindrical member, the latter being revoluble to disengage the two flanges.

In testimony whereof I affix my signature in presence of two witnesses.

WILLIAM F. ANKLAM.
